UNITED STATES PATENT OFFICE

141,630

DESIGN FOR A PENCIL

Wilson K. Chapman, Washington, D. C.

Application November 10, 1944, Serial No. 116,258

Term of patent 14 years

(Cl. D74—24)

To all whom it may concern:

Be it known that I, Wilson K. Chapman, a citizen of the United States, residing at Washington, District of Columbia, have invented a new, original, and ornamental Design for a Pencil, of which the following is a specification, reference being had to the accompanying drawing forming part thereof.

The characteristic features of the invention are a round pencil body with a series of aligned depressions formed on lines parallel with the axis of the body and displaced from each other circumferentially of the body at 120°, covering sub-

stantially two-thirds of the length of the pencil body.

Figure 1 is a side elevational view of a pencil showing my new design.

Figure 2 is a side elevation seen at a position revolved 120° from that of Figure 1, and

Figure 3 is a development of the surface of the article.

I claim:

The ornamental design for a pencil, as shown and described.

WILSON K. CHAPMAN.
